UNITED STATES PATENT OFFICE.

JOHN J. GILL, OF MULLAN, IDAHO, ASSIGNOR OF ONE-HALF TO HENRY BILLBERG, OF MULLAN, IDAHO.

ATTACHMENT FOR DRILLS.

1,207,538.

Specification of Letters Patent.

Patented Dec. 5, 1916.

Application filed August 23, 1915. Serial No. 46,888.

To all whom it may concern:

Be it known that I, JOHN J. GILL, a citizen of the United States, residing at Mullan, in the county of Shoshone and State of Idaho, have invented certain new and useful Improvements in Attachments for Drills, of which the following is a specification.

This invention has reference to attachments for drills, and its object is to provide an attachment for pneumatic rock drills, whereby the drill tool has imparted to it a rotative movement by the attachment during its reciprocatory movement by the drill mechanism.

In some types of rock drills the tool is reciprocated by the action of air upon a piston carrying the tool, while in other types the drill does not travel with the reciprocating piston, but is subjected to the impact of the piston whereby the tool is caused to act by a series of hammer blows delivered to it.

In order that the tool may be automatically rotated about its longitudinal axis the present invention provides a turning mechanism under the control of the air under pressure fed to, or the exhaust air from the drilling machine, and not only is the drill rotated while being subjected to blows of the reciprocating member; but in case of the tool sticking air under full pressure may be applied to the turning mechanism.

While the structure of the present invention may be built in the pneumatic drills at the time such drills are manufactured, it is adapted as an attachment to the hammer type of pneumatic drills already in existence, and among other advantages it is so arranged as to be quite free from injury from debris resulting from the drilling operation.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications come within the scope of the appended claims.

In the drawings, Figure 1 is an elevation of the tool end of a rock drill with the invention applied. Fig. 2 is a section on the

line 2—2 of Fig. 1, the section being confined to the tool rotating mechanism, but omitting some of the working parts. Fig. 3 is a section on the line 3—3 of Fig. 1. Fig. 4 is a section on the line 4—4 of Fig. 1. Fig. 5 is a top plan view of the attachment with the drill tool in cross-section. Fig. 6 is a section on the line 6—6 of Fig. 2.

Referring to the drawings there is shown a pneumatic drill 1 which may be taken as typical of any suitable form of rock drill, wherefore no attempt is made to show the working structure of the drill, since such structure does not enter into the present invention. Such a drill customarily terminates at one end in a flange 2 and to this flange there is applied a flanged end 3 of a crown or end member 4 made fast to the flange 2 by bolts 5. The crown or end member 4 alines with the body of the drill 70 and forms part of the structure of the present invention. The member 4 is usually cylindrical in cross-section and has a longitudinal bore 6 which is countersunk, as shown at 7, at the end remote from the flange 3. The member 4 is also formed at the end remote from the flange 3 with a radially extended flange 8 having at one side a further extension 9.

Made fast to the flange 8 with its extension 9 is one part 10 of a two-part casing 11, the two parts having inturned meeting flanges 12, 13, fastened together by screws or bolts 14.

The casing 11 is of generally triangular 90 cross-section with one side 15 bowed outwardly, and the apex of the triangle of rounded or cylindrical form, as shown at 16. At the sides of the triangle diverging from the apex 16 the casing contains two pairs of cylinders 17, 18, respectively, diverging like the sides of the casing with each cylinder opening into the interior of the cylindrical portion 16 of the casing.

Extending through the casing and the section 10 thereof is a sleeve 19 journaled in a collar 20 fitted in the countersink 7, this collar acting as a gland to confine packing 21 in the countersink. The sleeve 19 has a bore 22 conforming generally to the cross-sectional shape of a drill tool 23, which latter may be of the customary form with equi-spaced surface ribs 24.

The end of the casing remote from the flange 8 to which it is secured is formed into 110

an end plate 25 upon which is mounted a head 26 which, as well as the plate 25, has a passage therethrough for the drill tool 23. The passage through the plate 25 is sufficient 5 to accommodate the sleeve 19 and this sleeve enters but does not extend through the head 26. That end of the sleeve where entering the head 26 is countersunk and receives an internal collar 27 conforming interiorly to 10 the tool 23 and serves in conjunction with the corresponding end of the sleeve 19 to confine packing 28 against the inner wall of a countersink 29 in the head 26, which head is bored from the countersink to permit the 15 passage through the said portion of the head of the collar 27.

The head 26 has a chamber 30 formed therein in position to aline with the cylindrical portion 16 of the casing 11. The 20 chamber 30 is entered axially by a threaded passage normally closed by a screw plug 31 formed with a bore 32 to receive one end 33 of a crank shaft 34, said crank shaft extending lengthwise of the cylinder 16 and at the 25 end remote from the extension 33 provided with another extension 35. The extension 33 is passed through the plate 25 which is suitably bored for the purpose, and the crank shaft has crank portions 36, 37 in proper position to match the respective pairs 30 of cylinders 17 and 18. The extension 35 passes through a bearing sleeve 38 appropriately carried by the section 10 of the casing and has a step bearing in a sleeve 39 35 mounted in a boss 40 on the bottom of the extension 9 of the flange 8. Within the casing section 10 the extension 35 is provided with a circumferential series of gear teeth 41 meshing with a gear wheel 42 mounted on 40 and made fast to the sleeve 19 within the casing section 10.

In each cylinder 17 and 18 there is mounted a piston 42^a connected by a pitman 43 to a respective one of the cranks 36 or 37, as 45 the case may be. Each cylinder 17 and 18 is closed at the end remote from the cylindrical portion 16 of the casing by a screw plug 44 or by any other appropriate means.

In the head 26 are divergent cylindrical 50 bores 45 corresponding in position to the cylinders 17 and 18 and each bore 45 contains a hollow piston 46 connected by a pitman 47 to a cam ring 48 encircling a cam 49 on the extension 33 of the shaft 34. Each cylindrical 55 bore 45 is closed by a plug 50 and each bore communicates by a port 51 to a corresponding one of the cylinders 17.

On the rounded portion 15 of the casing 60 10 is a boss 52 with a threaded countersunk portion 53 for the reception of a pipe 54 by means of which either primary air or exhaust air is directed into the structure. The boss 52 communicates with a passage 55 having divergent branches 56 within the head 26 65 and leading to the cylindrical bores 45 in

the path of an elongated port 57 in each of the pistons 46. The port 57 communicates with the interior 58 of a respective piston 46 and that end of the piston remote from the pitman 47 is open so that during a portion 70 of the stroke of the piston its interior is in communication with the port 51.

The head 26 adjacent to each bore 45 is provided with another passage 59 leading to a corresponding one of the cylinders 18, and 75 this passage 59 is in the path of the port 57, so that at certain phases of the reciprocation of the piston 46 the supply passage 56 is brought into communication with the passage 59, but at this time the port 51 is closed 80 by the piston 46. Each cylinder 17 and 18 has an exhaust port 60.

When air is admitted to the drilling machine in the usual way, the drill tool is subjected to hammer blows by means of which 85 the drilling is performed in the usual manner.

By the admission of air to the passage 55, such air being either primary or exhaust air, and in the latter case still under considerable pressure, such compressed air finds its way to the valve pistons 46 and by the then active portions to one pair of cylinders 17 or 18, with the result that the crank shaft 34 is driven rotatively and the rotative movement is imparted to the gear wheel 42, thus correspondingly rotating the drill tool, which, because of its shape, cannot rotate independently of the sleeve 19 and the latter being keyed to the gear wheel must rotate 100 with it.

The pistons 42^a in the cylinders 17 and 18 and the reciprocating valve pistons or valves 46 provide two pairs of simple single-acting engines, so mounted with relation to the 105 crank shaft that the power is applied thereto in a practically continuous manner. Even if the drill tool should stick, there is ample force in the compressed air, and especially the primary air supply, to loosen 110 such tool so that a proper operation of the tool is insured at all times.

The attachment is applied to the tool end of the drilling machine and not having any material side projections does not unbalance the drilling machine, nor is the drill rotating mechanism sufficiently bulky or of sufficient weight to have any material effect upon the working of the machine.

The head 26 is closed at all points except 120 where traversed by the drill tool and at this point the fit of the drill tool may be quite close, so that no chips or other parts liable to wear the working structure will find access to the interior of the casing 10. Moreover, all parts extending through the casing 10 are packed so that the casing 10 may receive a considerable amount of lubricant, keeping the parts thoroughly lubricated at 125 all times without attention.

What is claimed is:—

1. An attachment for pneumatic drills of the reciprocating hammer type, comprising a casing having means for its attachment to the tool end of the drilling machine and also provided with means to be traversed by the drilling tool, and a plurality of single-acting pneumatic engines lodged within the casing and each having positive 10 connections to the means to be traversed by the drilling tool for rotating said means together with the tool, said engines being related to the means to be traversed by the tool for positively rotating the tool always 15 in the same direction at each power stroke of the respective engine.

2. An attachment for pneumatic drills of the reciprocating hammer type, comprising a casing adapted to the tool end of the 20 pneumatic drill, said casing having a rotatable sleeve therethrough shaped to be traversed by and fit the drill tool for rotating said tool, a plurality of pairs of divergent cylinders within the casing, pistons and piston 25 rods in the cylinders, a crank shaft having cranks each engaged by the piston rods of a corresponding pair of pistons, slide valves connected to the crank shaft for directing air in order to the cylinders, and 30 gearing connections between the crank shaft and the sleeve surrounding the drill tool.

3. An attachment for pneumatic rock drills of the reciprocating hammer type comprising a crown member having means 35 for attachment to the tool end of the pneumatic drill and bored to be traversed by said tool, a casing carried by the crown member, a rotatable sleeve extending through the casing and journaled at the ends in the crown 40 member and in the end of the casing remote from the crown member, and adapted to surround the tool in engagement therewith, a gear wheel within the casing carried by the sleeve, a crank shaft journaled in the casing 45 and having gear teeth engaging the gear wheel, said casing being provided with pairs of cylinders in operative relation to the crank shaft, single-acting pistons within the cylinders and each connected to a respective crank of the crank shaft, a head applied to the casing, slide valves in the head 50 provided with air passages for feeding air to them, and other passages leading to respective cylinders, and connections between the crank shaft and the slide valves with the slide valves and pistons in the cylinders 55 timed in operation to provide substantially constant power to the crank shaft and

through the latter and the gearing to the sleeve receiving the tool, whereby to cause 60 rotation of said tool while at work.

4. An attachment for pneumatic drills of the reciprocating hammer type, comprising a casing adapted to be attached to the drill in surrounding relation to the drill tool, 65 said casing having convergent cylinders within it with a crank shaft located at the apex of the convergent cylinders, single-acting pistons within the cylinders connected to the crank shaft, convergent slide valves 70 mounted on the casing and communicating with the cylinders for supplying compressed air thereto, the cylinders and slide valves being arranged on opposite sides of the portion of the casing traversed by the drill tool, a 75 sleeve surrounding the drill tool mounted for rotation in the casing, and gearing connections between the crank shaft and sleeve with the latter constantly engaging the tool, whereby rotation of the sleeve by the pistons 80 acting through the gearing imparts rotative movement to the drill tool irrespective of the movements imparted thereto by the drilling machine.

5. An attachment for drilling machines of 85 the reciprocating hammer type, comprising a casing with a sleeve extending therethrough in a line approximating the longitudinal center line of the casing, said casing having pairs of circumferential cylinders 90 therein and itself formed into a cylinder extending transversely of the first-named cylinders at the angle of convergence of the first-named cylinders, a head for the casing having cylindrical bores therein converging 95 into another cylindrical portion alining with the second-named cylindrical portion of the casing, the head having passages and ports communicating with the cylinders therein, slide valves in the cylinders and the head, 100 single-acting pistons in the first-named cylinders, a crank shaft mounted on the casing in the longitudinal center line of the cylindrical portions of the casing and head at the apex of the approaching cylinders there- 105 in, and gearing connections between the crank shaft and sleeve, whereby a drill tool extending through the sleeve is rotated by compressed air supplied through the slide valves to the cylinders.

In testimony whereof I have affixed my signature in presence of two witnesses.

JOHN J. GILL.
